Attest.

United States Patent Office.

JOHANN M. SCHMIDT, OF NEW ALBANY, INDIANA.

Letters Patent No. 96,983, dated November 16, 1869.

IMPROVEMENT IN SPRINGS.

The Schedule referred to in these Letters Patent and making part of the same.

To all whom it may concern:

Be it known that I, JOHANN M. SCHMIDT, of New Albany, in the county of Floyd, and in the State of Indiana, have invented certain new and useful Improvements in Springs; and do hereby declare that the following is a full, clear, and exact description thereof, reference being had to the accompanying drawings, and to the letters of reference marked thereon, making a part of this specification.

The nature of my invention consists in the construction and arrangement of a spring for locomotives, railroad-cars, &c., as will be hereinafter fully set forth.

In order to enable others skilled in the art to which my invention appertains, to make and use the same, I will now proceed to describe its construction and operation, referring to the annexed drawings, in which—

Figure 1 is a side view of a car-spring;

Figure 2 is an enlarged section, showing the manner of securing the leaves of the spring; and

Figure 3 is a plan view of the spring.

C represents an ordinary leaf-spring for cars, locomotives, &c., composed of the leaves *a a*. These leaves are, however, not connected by rivet, bolt, or any means heretofore commonly used. They are, in fact, not connected together at all.

Each leaf, *a*, is, at one or the other end, provided on the upper side with a projection, *i*, formed by a

countersink from the under side, which projects into a slot in the leaf above, thus holding the leaves in position, and at the same time allowing them to slide or give, as occasion requires.

The ends of the spring C are narrower than the centre, which will prevent the friction of the wheels from taking the temper out of the spring.

On the ends of the spring, are placed caps or protections, D D, which are made to fit exactly the hangers E E, and the ends of the springs are slotted, so that the hangers may pass through. These slots, being made somewhat larger than the hangers, allow for a free motion, and the hangers will not injure the spring by coming in contact with it.

Having thus fully described my invention,

What I claim as new, and desire to secure by Letters Patent, is—

The combination of the spring C, slotted at the ends, and its leaves held in position, as described, with the caps D D and hangers E E, substantially as herein set forth.

In testimony that I claim the foregoing, I have hereunto set my hand, this 15th day of July, 1869.

JOHANN M. SCHMIDT.
